Motor Driven Gearing For Driving Turn Table

Inventor:
William A. Fricke
By G. L. Gray
Atty.

UNITED STATES PATENT OFFICE.

WILLIAM A. FRICKE, OF CHICAGO, ILLINOIS.

PHONOGRAPH.

Application filed December 5, 1919. Serial No. 342,605.

To all whom it may concern:

Be it known that I, WILLIAM A. FRICKE, citizen of the United States, residing at Chicago, in the county of Cook and State of Illinois, have invented a certain new and useful Improvement in Phonographs, of which the following is a full, clear, concise, and exact description.

My invention relates to phonographs and has for its general object the provision of 10 counting mechanism operated thereby, a purpose that may be served by this counting mechanism being the actuation of a brake or other means for stopping the rotation of a record upon the completion of its run in a phonograph. My invention is of particular service when employed in connection with a phonograph that includes a disc record supporting turn table which is 15 preferably itself employed for effecting the application of the brake.

In the preferred embodiment of my invention the counting device includes a threaded shaft having a gear wheel for turning it, 20 this wheel being rotated by a threaded formation upon the periphery of the turn table and a rider in threaded engagement with the shaft and brought thereby into actuating relation with the brake or other record stopping means when a record has been 25 played. There is desirably associated with the rider two reversely related or oppositely reading scales which are placed along the line of travel of the rider for denoting the 30 number of rotations of the turn table, one scale being employed to ascertain the number of revolutions a record makes to complete the playing thereof and the other scale being employed to determine the initial position of the rider that should be in correspondence with the number of rotations of 35 the record so that the record may be stopped just as the playing thereof is completed.

I will explain my invention more fully 40 by reference to the accompanying drawing illustrating one embodiment thereof and in which Fig. 1 is a plan view of enough of a phonograph to illustrate the application of my invention thereto, the preferred embodiment of the invention being illustrated; Fig. 2 is a sectional view on line 2—2 of Fig. 1; Fig. 3 is a sectional view on line 3—3 of Fig. 1; Fig. 4 is a sectional view on line 4—4 of Fig. 1; and Fig. 5 is a view in 45 elevation of the turn table with the counting mechanism removed.

Like parts are indicated by similar characters of reference throughout the different figures.

The drawing illustrates a disc record 1 turned by the record rotating mechanism of the phonograph, of which rotating mechanism there is illustrated a part 2 of a turn table which supports the record and causes the record to turn therewith. Any suitable 60 form of brake or other record stopping means may be employed, that illustrated being similar to those which are commonly used. The brake illustrated includes a brake pad 3 mounted upon the outer end of an arm 4 pivoted at 5 to a mounting leaf 6. A spring 7 serves normally to hold the brake pad out of engagement with the inner cylindrical surface of the peripheral rim or skirt 8 of the turn table. A stop 9 upon the 70 mounting leaf 6 serves to define the position to which rim 4 may be drawn by the spring 7. Said arm has a branch 10 which is to be operated, when a record has been played, to bring the brake pad 3 into engagement with 75 the rim of the turn table, initial engagement of the turn table rim with the pad being sufficient as the turn table itself will carry the pad with it for a slight distance to increase the braking pressure of the pad. The 80 extent to which the brake pad may be turned by the turn table is defined by a stop 11 also carried upon the mounting leaf 6.

By mechanism which is to be described a rider 12 gradually approaches the arm 90 branch 10 and ultimately engages the same when the record has been finished, said arm branch projecting slightly beyond the circle of the turn table to make it accessible for engagement by said rider. This rider includes, as a part thereof, a nut 13 which is in threaded engagement with a threaded shaft 14, the shaft being rotated by the turn table in a manner to be set forth so as to bring the engaging part 12 of the rider into 95 brake actuating engagement with the arm branch 10. A gear wheel 15 is employed for turning the shaft 14, the wheel and shaft being desirably co-axial with the wheel in fixed relation to the shaft. This gear wheel is engaged by a threaded formation 16 provided upon the exterior cylindrical surface of the turn table rim 8. This spiral formation 16 constitutes a thread which is in engagement 105 with the gear wheel 15 whereby said gear wheel is turned as the turn table is rotated. The threaded formation 16 may be furnished 110

by a spirally shaped piece of angle iron having a horizontal branch in engagement with the gear wheel 15 and its vertical branch clamped against the face of the rim 8 by 5 means of U-shaped clips 17. These clips embrace the rim 8 of the turn table and the vertical branch of the angularly threaded track 16, clamping screws 18 passing through the inner vertical branches of the 10 clips into engagement with the inner cylindrical face of the rim 8; these clamping screws being in threaded engagement with the clips to enable them to perform their clamping function.

15 As a record is being played the rider will move toward the left and ultimately will engage the portion 10 of the track to actuate the brake when the record is concluded.

20 The records at present upon the market do not indicate the number of their revolutions required to play them, on which account the users of my invention will have to determine the number of turns to be made by the record in order that the rider may be 25 adjusted to have lineal travel corresponding to the varying extent of the rotation of the records. Some records require more or less lineal travel of the riders than others. To this end I provide 30 two oppositely reading or reversely related scales 19, 20. When the number of turns required by the record is to be counted the rider is placed at the initial end of the scale 19 whereupon the phonograph is started, the rider being moved in a lineal direction toward the turn table until the phonograph is stopped at the conclusion of the 35 performance of a record. The number of turns is indicated by the mark upon the scale 19 with which the index 21 (upon the rider) stops in register. The index 22, also carried upon the rider, is then placed in register with that scale mark upon the scale 20 that corresponds in number with the 40 number of rotations indicated by the index 21. To make the rider readily adjustable along the scales in determining the place at which it should be set, it is caused to have separable 45 engagement with the threaded portion of the shaft 14. To this end the construction illustrated most clearly in Fig. 4 may be employed with a stem 23 projecting upwardly through the slot 24 between the scales 19 and 20; this stem terminating in a knob 25 by 50 means of which the rider may be readily lifted from engagement with the shaft and in opposition to the spring 26 that normally maintains the threaded engagement of the rider with the shaft. The stem 23 also 55 preferably has snug sliding engagement with the opposing edges of the scales so that these scales, in conjunction with the spring, serve to maintain the rider in normal position not only with respect to the shaft 14 but also 60 with respect to the brake 10 of the brake arm 65

4. For simplicity of construction the mounting leaf 6 is a continuation of the framework 27 which supports the scales.

As illustrated, the spring 7 will release the brake as soon as the rider is moved away from the record, whereby the record will be automatically started following the outward positioning movement of the rider, the stylus having been previously adjusted to starting position.

The counting and record stopping mechanism herein disclosed does not employ the stylus for actuating it, the mechanism that operates the phonograph operating the device of my invention independently of the stylus, an obvious advantage.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A phonograph including a turn table for supporting and rotating a disc record; means for stopping the turn table; a threaded shaft having a gear wheel for turning it, there being a threaded formation upon the periphery of the turn table in turning engagement with said gear wheel to turn said shaft; a rider in threaded engagement with the shaft and brought thereby into actuating relation with said means; and two reversely related scales placed along the line of travel of the rider for measuring the number of rotations of the turn table.

2. A phonograph including a turn table for supporting and rotating a disc record; means for stopping the turn table; a threaded shaft rotated by the turn table; a rider in threaded engagement with the shaft and brought thereby into actuating relation with said means; and two reversely related scales placed along the line of travel of the rider for measuring the number of rotations of the turn table.

3. A phonograph including a turn table for supporting and rotating a disc record; means for stopping the turn table; a threaded shaft having a gear wheel for turning it, there being a threaded formation upon the periphery of the turn table in turning engagement with said gear wheel to turn said shaft; a rider in threaded engagement with the shaft and brought thereby into actuating relation with said means; and a scale placed along the line of travel of the rider for measuring the number of rotations of the turn table.

4. A phonograph including a turn table for supporting and rotating a disc record; means for stopping the turn table; a threaded shaft rotated by the turn table; a rider

in threaded engagement with the shaft and brought thereby into actuating relation with said means; and a scale placed along the line of travel of the rider for measuring the

5 number of rotations of the turn table.

5. A phonograph including a turn table for supporting and rotating a disc record; means for stopping the turn table; a threaded shaft having a gear wheel for turning 10 it, there being a threaded formation upon the periphery of the turn table in turning engagement with said gear wheel to turn said shaft; and a rider in threaded engagement with the shaft and brought thereby 15 into actuating relation with said means.

6. A phonograph including a turn table for supporting and rotating a disc record; means for stopping the turn table; a threaded shaft rotated by the turn table; and a 20 rider in threaded engagement with the shaft and brought thereby into actuating relation with said means.

7. A phonograph including a turn table for supporting and rotating a disc record; 25 means for stopping the turn table; and a device for operating said means brought into actuating relation with said means by the turn table.

8. A phonograph including a disc record 30 supporting turn table having a thread formation upon its periphery; in combination

with counting mechanism driven by said thread formation; and means for stopping the record and actuated by the counting mechanism.

35

9. A phonograph including a disc record supporting turn table; in combination with counting mechanism driven by the turn table; and means for stopping the record and actuated by the counting mechanism.

40

10. A phonograph including a rotating record support having a thread formation thereon; in combination with counting mechanism driven by said thread formation; and means for stopping the record and actuated by the counting mechanism.

45

11. A phonograph including a rotating record support; in combination with counting mechanism driven by said record support; and means for stopping the record and actuated by the counting mechanism.

50

12. A phonograph including a rotating record support; means for stopping the record; a threaded shaft operated by the phonograph mechanism; and a rider in threaded engagement with said shaft and brought thereby into actuating relation with said means.

55

In witness whereof, I hereunto subscribe my name this 20th day of November, A. D., 60 1919.

WILLIAM A. FRICKE.
